CALCULATING AND BOOKKEEPING MACHINE

Kurt Gelpke, Berlin-Neukolln, Germany, assignor
to The National Cash Register Company, Dayton,
Ohio, a corporation of Maryland

Application September 5, 1935, Serial No. 39,212
In Germany December 11, 1934 (Design)

6 Claims. (Cl. 197—128)

The invention relates to calculating and book-keeping machines provided with a laterally shiftable traveling carriage, for example, as shown and described in the United States application Serial No. 653,838 of January 27, 1933 and more particularly to a front feed device for such carriages.

For guiding paper around the platen, a front feed paper chute is provided for inserting paper at the front thereof. This mechanism also serves as a line finding device for properly locating the ledger sheet or other material inserted therein in relation to the printing line. The platen is rockably arranged and rocking the platen and its carrying frame away from printing position moves the guiding mechanism to a position where it will properly direct material around the platen.

The main object of the invention is to provide resilient means in the front feed chute for enabling a feed of a paper or card in front of a paper wound around the platen.

Another object of the invention is to arrange said resilient means to enable a feed of a paper or card in front of said before named paper or card.

Further objects of the invention will be pointed out in the following detailed description with reference to the annexed drawing.

30 A preferred form of an embodiment of the invention is shown in the annexed drawing.

Of said drawing:

Fig. 1 is a sectional view, showing the position of the rear work sheet table and the front feed chute when the platen is in printing position.

Fig. 2 is a sectional view, illustrating the position of the rear work sheet table and the front feed chute when the traveling carriage platen is rocked away from printing position.

40 Fig. 3 is a partial perspective view illustrating the platen and the arrangement of the resilient retaining means.

General description

45 A system usually employed for example in a bank, provides a ledger sheet for each depositor upon which the daily balancing of his account takes place. A record of the day's work is generally kept on a record or journal sheet, which together with its superimposed carbon is first wound around the platen roll. As the record sheet remains in the machine during the entire run, it is inserted at the rear thereof and fed around the platen by means of pressure rolls until its top edge passes beyond the printing line in the customary manner. As there are generally a large number of accounts to balance, and consequently a large number of ledger sheets to be handled, it is necessary that means be

provided whereby these ledger sheets may be quickly inserted around the platen roll, located in relation to the printing line and, then a third card relating to the special transactions inserted in front of the ledger sheet which after the balancing operation is completed, is quickly removed from the machine with the least amount of effort possible on the part of the operator.

To accomplish this result the machine of the instant invention in its preferred form has been provided with a shiftable platen which is automatically rocked or tilted upwardly away from the printing line to a more accessible or front feeding position when the traveling carriage is tabulated to a predetermined columnar position. Simultaneously with the rocking of the platen away from printing position the front feed guide chute is rocked into guiding position and after the platen has completed its movement away from printing position the pressure rolls are automatically disengaged from the platen roll and the material wound there-around. The third sheet may now be removed by pulling it from around the platen, and another sheet may then be inserted in the front feed guide chute, pushed around the platen roll until the proper line is located by means of the line finding device after which the platen is returned to printing position by a hand return lever conveniently located on the traveling carriage frame.

Inserting and removal of the third and also eventually ledger sheets does not disturb the record sheet and its superimposed carbon, as they are held in contact with the platen by auxiliary pressure rolls which are not released when the platen is rocked away from printing position.

Detailed description

Referring to Figs. 1 and 2, pivoted on the platen shaft 10, just inside the platen frame end plates 42 and 43 are arms 30 and 31, carrying at their upper ends rollers 34 and 35 projecting into slots 36 and 37 in brackets 38 and 39 secured on the traveling carriage frame. The arms 30 and 31 are connected by a guiding bar 23 which is secured to right angled surfaces formed on said arms 30 and 31. Adjustably attached to each end of the bar 23 are lateral guides 22 and 22', the lateral location of which may be changed in relation to the platen 14 to accommodate different widths of paper or ledger sheets. The rocking of the platen and its carrying frame away from printing position and the cooperation of the rollers 34 and 35 with the inclined slots 36 and 37 changes the positions of the arms 30 and 31 so that the bar 23 and lateral guides 22 and 22' are tilted into alignment, with a front feed guide table 40 which extends the width of the platen 14 and is secured to the platen frame 60

end plates 42 and 43. Adjustably mounted on the rear feed table 13 are rear lateral guides 41 (Figs. 1 and 2), the lateral locations of which may be shifted to conform to the locations of 5 the front guides 22 and 22'.

When the platen is away from printing position, as shown in Fig. 2, the top edge of the bar 23 is so positioned in relation to the printing line that it serves as a means for properly locating 10 material inserted at the front of the platen in proper relation to the printing line. As may be seen from Fig. 2 when the platen is out of printing position the pressure rolls 26 (Fig. 2) are disengaged therefrom thereby permitting paper to be inserted within the lateral guides 22 and 22' and simply pushed around the platen 14, guided 15 by the front feed table 23 and 40 until the top edge of the bar 23 is in alignment with the bottom of the last row of printing upon said ledger 20 sheet. This locates the ledger sheet in relation to the printing mechanism so that when the platen is returned to printing position the space just below the printing on said ledger sheet will be in alignment with the impression mechanism.

25 The account or work sheet 11 together with a carbon sheet is inserted from the rear when the platen 14 (Fig. 2) is rocked away from printing position and fed along the rear table 13 around the platen 14. The papers are retained tightly 30 by several auxiliary pressure rolls arranged upon a rod 15. The rod 15 is supported by two arms 16 pivoted on brackets 17 of the rear table 13 and acted upon by means of springs 18 tensioned between the brackets 17 and the arms 16.

35 A pair of resilient straps 19 (Fig. 3) are fastened in any suitable way to the rear table 13 and guided around the platen 14. The free ends of the straps are secured to a rod 20. In order to enable inserting a ledger card or other paper 40 from the front, notches 21 are provided in the lateral guides 22 and 22' of the front feed paper guide table 23 and 40 to receive the ends of the rod 20, when the platen is rocked away from printing position as shown in dashed-dotted lines 45 in Fig. 2.

When the platen is out of printing position and the ends of the rod 20 engage the notches 21 of the guidances 22 and 22', a ledger card 24 can be inserted from the front and aligned to the 50 proper printing line. Thereupon the rod 20 is freed from the notches and laid upon the card 24 as shown in full lines in Fig. 2, whilst the work sheet 11 and the carbon paper 12 are retained in proper place upon the platen 14 by the auxiliary 55 rollers of the rod 15. In front of the straps 19 and the ledger card 24 any other record material 25 can be inserted, whereupon the platen is rocked into printing position as shown in Fig. 1, wherein the three papers are held tightly by 60 lower pressure rollers 26.

After the printing is done, the platen is rocked away from printing position thus enabling the withdrawal of the front paper 25, as the rollers 26 move away from the platen 14, the card 24, 65 however, is retained in proper position by the straps 19.

70 While the form of mechanism herein shown and described, is admirably adapted to fulfill the objects primarily stated, it is to be understood that it is not intended to confine the invention to the embodiments herein disclosed, for it is susceptible of embodiment in various other forms all coming within the scope of the claims which follow.

What is claimed as new is:

1. In a machine of the class specified in combination with a laterally shiftable carriage provided with a platen rockable into and out of printing position, a front feed guide chute for feeding record material from the front, a front feed guiding table, a rear feed guiding table, of resilient straps wound around said platen and fastened to the rear feed guiding table, and of means for connecting said straps, said means cooperable with said front feed guide chute to hold the straps in the front feed chute for front feeding with the carriage out of printing position. 5

10 15 20 25 30 35 40 45 50 55 60 65 70 75 80 85 90 95 100

2. In a machine of the class specified in combination with a laterally shiftable carriage provided with a platen rockable into and out of printing position, a front feed guide chute for feeding record material from the front, a front feed guiding table, a rear feed guiding table, of resilient straps wound around said platen and fastened to the rear feed guiding table, of a rod connecting said straps and of notches in said front feed guide chute adapted to receive said rod with the carriage out of printing position.

3. In a machine of the class described, having a platen, a guide chute, a front feed guide means cooperable with said chute to guide record material in front feeding operations, a rear feed guide means normally operable to guide record material from the rear of the machine, and means for coupling the rear feed guide means to the chute for certain front feeding operations. 25 30 35 40 45 50 55 60 65 70 75 80 85 90 95 100

4. In a machine of the class described having a platen, a front feed guide chute, a front feed guide plate cooperating with the chute to guide record material in front feeding operations, a rear feed guide plate normally operable to guide record material from the rear, and means cooperable with the rear feed guide plate and the chute to enable the rear feed guide plate to be used in certain front feeding operations, whereby the chute and both guide plates can be used for simultaneously guiding record material in said certain front feeding operations. 35 40 45 50 55 60 65 70 75 80 85 90 95 100

5. In a machine of the class described having a platen movable into and out of printing position, the combination of a front feed guide chute, a front guiding table cooperable with said chute for guiding record material from the front of the machine, a rear guiding table for guiding record material from the rear of the machine, means connected to said rear table and extending forwardly around the platen, said means being shiftable into engagement with said front feed guide chute when the platen is out of printing position whereby said rear guiding table can also operate as a guide in front feeding operations. 45 50 55 60 65 70 75 80 85 90 95 100

6. In a machine of the class described having a platen, a guide chute for record material, a front feed guide plate cooperating with said chute to guide record material in front feeding operations, a rear feed guide plate normally effective to guide record material when it is fed from the rear, and manipulative means connected to the rear feed guide plate and engageable with the guide chute to enable the rear feed guide plate to guide record material in certain front feeding operations, said guide chute and both guide plates being simultaneously effective to guide separate pieces of record material in said certain front feeding operations. 60 65 70 75 80 85 90 95 100
